[57] CLAIM

The ornamental design for a table base, as shown and described.

DESCRIPTION

FIG. 1 is a top plan view of a table base showing my design;

FIG. 2 is a side elevational view;

FIG. 3 is an end elevational view; and

FIG. 4 is a perspective view of the table base on an enlarged scale.

The side and end not shown in FIGS. 2 and 3 are like the respective side and end shown while the appearance of the base is a mirror image of the top as shown in FIG. 1.
